(57) **CLAIM**

The ornamental design for a powered brush handle, brush,
charger, and cap, as shown and described.

DESCRIPTION

FIG. 1 is a top front right perspective view of a powered brush
handle with brush, charger and cap, showing our new design;
FIG. 2 is a front elevation view thereof;
FIG. 3 is a rear elevation view thereof;
FIG. 4 is a top plan view thereof;
FIG. 5 is a bottom plan view thereof;
FIG. 6 is a left side elevation view thereof;
FIG. 7 is a right side elevation view thereof;
FIG. 8 is a top front right perspective view thereof with the
cap removed for convenience; and,
FIG. 9 is an exploded top front right perspective view thereof.
The broken lines immediately adjacent the shaded areas rep-
resent the bounds of the claimed design while all other broken
lines are included for the purpose of illustrating portions of
the powered brush handle with brush, charger and cap; the
broken lines form no part of the claimed design.
